AMUSEMENT RIDE BUILDING

Samuel P. Goforth and Joseph A. Goforth, Shelby, N.C.,
assignors to Goforth Brothers, Inc., Shelby, N.C., a cor-
poration of North Carolina

Filed Jan. 31, 1968, Ser. No. 10,377

Term of patent 14 years

Int. Cl. D21—04

U.S. Cl. D34—5

FIG. 3

FIG. 1 is a front perspective view of an amusement ride building showing our design;

FIG. 2 is a fragmentary left side elevational view thereof; and

FIG. 3 is a front elevational view thereof.

The rear and sides of the amusement ride building shown in the drawings are substantially plain and unornamented.

We claim:

The ornamental design for an amusement ride building, substantially as shown and described.
